SAFETY THROWOFF

Carl D. Wagner, Tulsa, Okla.

Application July 2, 1941, Serial No. 400,849

5 Claims.

(Cl. 74—593)

The present invention relates to a power coupling device and more particularly to a safety coupling device for a power rod line in the operation of oil well pumps.

As defined in my copending application, Serial No. 370,719, filed December 18, 1940, of which the present application is a continuation-in-part, the present invention contemplates the provision of a construction interposed within the surface rod line and preferably between a pumping jack and a source of power in order to permit actuation of the pump as well as selective controlled disposition of the pump and plunger with respect to the casing. It is desirable and necessary in the present art therefore to provide a construction adapted to permit controlled initiation and termination of the pumping action or movement of the rod line toward and away from pumping position. Prior devices capable of operating properly under the severe stresses imposed in the operation of deep well pumps have been of the type presenting a serious danger to the operator in requiring hooks to be caught and manipulated on the fly. While many improvements have been suggested, these in general have sacrificed load carrying capacity to such an extent as to seriously interfere with the practical continued operation of the structures.

It is accordingly an important object of the present invention to provide an improved and simplified throw-off device eliminating in large measure the structural elements heretofore necessary, providing a relatively simplified holding block or anchor in connection with axially aligned control members which are so arranged as to eliminate all undesired frictional binding forces and to resolve the holding and driving forces substantially on the axis of the rod line.

A further object of the present invention contemplates the provision of a throw-off device as above wherein the driving or force applying means for connecting releasable parts is at the same time selectively releasable, or operable to apply the driving and holding forces diametrically across the axis of the parts in such a manner as to axially distribute the forces.

A yet more specific object of the invention in accordance with the foregoing is to provide a throw-off device embodying holding keys which, while operative substantially throughout the lateral diametral extent of the driving members, is adapted to automatic release under predetermined conditions for facilitating separation and enabling the well to be automatically pulled into any desired pumping position.

A further object of the present invention is to provide a construction as above eliminating all unnecessary parts and simplifying the unit in the interests of compactness and portability.

Yet other and further objects will be apparent

from the following specification when taken in conjunction with the accompanying drawings, wherein

Figure 1 is a perspective view of a throw-off device embodying the features of the present invention.

Figure 2 is a plan view of the holding block shown in Figure 1.

Figure 3 is a sectional view taken centrally through the clamp connecting with the rod line passing to the well.

Figure 4 is a sectional view taken centrally and axially through the clamp construction connecting with the power rod line.

Figure 5 is a sectional view taken centrally and axially through the knock-off holding block and associated elements.

Figure 6 is a sectional detailed view taken on the line 6—6 of Figure 5.

Referring now more particularly to the drawings wherein one preferred form of the invention is shown for purpose of illustrating the invention, Figure 1 comprises a construction including a tail or holding block 10 mounted upon a suitable fixed supporting base 12. A power or driving clamp 14 connected to a power rod line 16 and a connecting bar 18 slidably through the tail block 10 are connected with a clamp 20 rigid with a power rod line 22 passing to the well or pumping jack. As shown more particularly in Figures 2, 5 and 6, the holding block 10 is of generally prismatic rectangular form having on its lower surface a downwardly projecting flange construction 24 received within the concrete base 12 which, it will be understood, is rigidly fixed or positioned with respect to the ground. The block is additionally bored adjacent its four corners to receive hold-down bolts 26 and nuts 28, wherefore the block remains rigidly mounted in the position shown. As clearly shown, the block comprises a longitudinal bore 30 receiving the control bar or sleeve 18 in journalled relationship for axial longitudinal reciprocation therein. In short, the sleeve or bar 18 is received and constrained in the axially disposed location as shown in the drawings.

Means is provided for holding the bar against retrograde axial movement in one direction only and involves a recess 32 formed within the holding block 10 as shown clearly in Figures 1, 2, 5 and 6. Attention is particularly directed to the fact that the recess or slot 32 extends completely diametrically across the journal aperture 30 and extends an equivalent distance outwardly of opposed margins thereof whereby to receive a holding key 34 as will hereinafter more fully appear. On the other hand, the lateral width of the slot or recess 32 is considerably smaller than the diameter of the bearing aperture 30 as shown in Figure 6, whereby the rod 18 is adequately

guided and journalled in the vicinity of the recess. It is of further importance to note that the recess 32 extends from the extremity of the block 10 in the vicinity of the power section of the rod line or the power coupling inwardly to a position spaced substantially from the opposite extremity of the block. In other words, the recess provides an abutment surface or shoulder 35 vertically diametrically disposed and having substantial abutment surfaces on opposite sides of the rod or sleeve 18 which preferably are disposed in a plane normal to the axis of the rod.

The power rod or sleeve 18 shown in the present embodiment comprises a tube or sleeve, although it may equally as suitably comprise a solid bar, and is provided with axially disposed spaced slots or recesses 36 extending diametrically therethrough for receiving the key or locking member 34 for example. To this end, therefore, each of the slots 36 has a transverse width substantially equal to that of the recess 32 and in operation the rod must normally be so disposed that the recesses or slots 36 and 32 align in substantially identical planes. It will be noted, moreover, that the slots 36 terminate in diametrically disposed abutment surfaces 38.

The key or removable locking member shown in Figures 2 and 4-6 inclusive embodies a relatively flat plate member having a body portion 40 freely receivable within the slots or recesses 32 and 36 in coplanar relation and defined by opposite parallel marginal surfaces 42 which, it is evident from the foregoing, are adapted to coact with the abutment surfaces 35 and 38 hereinbefore described.

The key is normally pivotally hung from a pair of oppositely disposed laterally extending pins, trunnions or pintles 44 located on the key. The key is provided at its top with a manually manipulatable ring grip 48. The trunnions 44 are received within journal recesses provided by upstanding opposed lugs or journals 50 located on the upper portion of the body section 10. It will be noted that the journal lugs 50 are oppositely disposed on either lateral side of the recess 32 and thus oppositely embrace the key 34 in holding position. The trunnion receiving recesses which open upwardly are defined by a vertical abutment wall 52 and by an inclined abutment wall 54 which diverge outwardly for facilitating bodily removal of the key or locking member from the association shown in Figures 1 and 4 to 6 inclusive. It is important to note that the vertical abutment surface which is parallel with the holding abutment surfaces 35 of the block is disposed adjacent the open end of the recess 32 or is, in other words, disposed away from the end of the block adjacent the pumping jack and it will be understood from the foregoing that this construction facilitates permanent maintenance of interengagement of the parts in the desirable relationship as long as the members are utilized to hold the bar 18 in fixed position.

The driving clamp fitting 14 comprises a tubular sleeve having an enlarged outer portion 56 embracing the driving portion of the rod line 16 and suitably welded or otherwise permanently fixed in position. An inner cylindrical section of reduced diameter 58 mounts a pair of journal lugs 60 identical in form with the journal lugs 50 hitherto described and adapted to be removably engaged by the pinions of a second key or driving pin 34 which may be substantially identical in form with the key previously de-

scribed. Intermediate of the opposed journal brackets 60, the sleeve portion 58 is slotted or recessed completely through its diameter, providing axially disposed abutment surfaces similar in function to those provided on the holding block and designated by the reference numerals 62 and 64, Figure 4. In short, it will be apparent that the abutment surfaces at the extremity of the slot adjacent the reduced extremity of the driving sleeve 14 are adapted to coact on key 34 with the oppositely disposed abutment surfaces provided by recesses 36 for effecting coaction of the driving bar 18 and sleeve 14.

Attention is particularly directed to the fact that the reduced extremity of the driving sleeve 14 forms a journal bearing receiving the extremity of the bar 18 for relative longitudinal movement. A cap 66 on the left hand most extremity of the bar or tube 18 provides a shoulder shiftable within the tubular rod line 16 and effective to limit separation of the parts. Thus, while the tube 18 may be adjustable selectively with respect to the driving sleeve 14 within wide limits, complete reaction therefrom is prevented by virtue of the cooperating shoulders formed by the cap 66 and the inner extremity of the restricted section 58 of the driving sleeve.

The opposite extremity of the control bar 18 is provided with a clamping fitting for axially connecting the pump jack portion of the rod line with the control bar 18 as shown in Figures 1 and 3. To this end, the fitting 20 comprises a cylindrical portion 68 receiving the end of the member 18 permanently preferably by welding. An axially extending flange 70 integral with the sleeve 68 is recessed to receive the upper extremity 72 of rod line 22 and an opposed clamping member 74 with a complementary recess oppositely embraces the rod line and is permanently held in clamping relation by a pair of fastening means 76.

From the foregoing, it will be apparent that the present simplified construction facilitates operation of the pump under complete control and in perfect safety to the operator. Thus, in normal operation, the rod line section 16 is reciprocated through a predetermined pumping stroke from any suitable source of power, carrying with it the integrally associated driving sleeve 14. Removal of the left hand most or driving key 34 as shown in Figure 1 permits the reciprocating parts to move relative to the control bar 18 which remains fixed by virtue of its engagement with the fixed block 10. In other words, the weight of the sucker rods and associated mechanism, which in deep wells may be of considerable magnitude, tends to draw the member 18 to the right as viewed in the figures, causing the abutment surfaces 38 of the slot to bear against a vertically aligned surface 42 of the key and urge the opposed parallel surface of the key into abutting engagement with the diametrically disposed shoulders or abutment surfaces 35 of the block. In short, it will be apparent that the force tending to draw the member 18 to the right is axially applied to the transversely extending surfaces 42 which forces are in turn applied to the reaction block equally on opposite sides of the central axis of the bar 18. In short, the interlocking or holding forces are resolved in such a manner as to eliminate all lateral binding forces tending to create undesired frictional forces and upsetting torques, furthermore eliminating the trunnions or pins 44 as a sub-

stantial factor in the holding action. Thus, substantially none of the locking forces are resolved in the vicinity of the holding pins 44, permitting instantaneous removal of key 34 as soon as the holding forces are released. At the same time, it will be understood from the foregoing that the vertical abutment surface cooperates to insure coplanar interengagement of the key with the abutment surfaces 35 and to frictionally prevent lateral removal of the key during periods of holding engagement.

With a key 34 applied to the driving clamp 14, the lateral margins thereof ride over the unslotted portions of the driving sleeve 18 until the relative movement of the parts results in alignment of one of the slots 36 at which time the key rotates about its pivots to drop thereinto, as shown with respect to the holding block 10 in Figures 5 and 6, the key then functioning in the same manner as heretofore described to interlock the driving sleeve 14 and the bar 18 upon movement of sleeve 14 to the left.

In accordance with the present invention, the keys in the respective slots have been so proportioned with respect to the normal path of reciprocation of the drive line 16 as to cause a plurality of slots 36 to pass the vicinity of the holding block. Accordingly, therefore, the key 34 associated with the holding block tends to rise or pivot outwardly of associated slot 36 and slide upon the unslotted surface of the member 18 until the next successive slot is reached. This time the key 34 drops into the slot, preventing further retrograde movement of the driving key 34, and performs a similar function resulting in stepwise advancement of the pump jack rod line to the left. This action is caused to cease at any point by removal of either of the keys 34. Thus, removal of the holding key results in continued reciprocation of the rod line in a predetermined path for normal pumping.

In accordance with the present embodiment by way of illustration, the slots 36 may be preferably six inches long and, spaced six inches between adjacent axial margins, and keys 34 may possess a lateral dimension of substantially three inches and have their trunnions so positioned as to facilitate free rotational movement into and out of the slots. It will be understood, however, that the foregoing dimensions are merely illustrative and that they may be varied within wide limits to produce the foregoing function.

It will be apparent that the present invention provides a knock-off construction of extreme simplicity and compactness when considered in comparison with the material stresses it is adapted to control, and it is evident that these advantages are achieved by virtue of the alignment of these stresses at all times upon a single central axis of operation. In short, it will be apparent that all of the operating members adapted to control holding and driving stresses are diametrically disposed with relation to the axis of the driving bar and these stresses are at all times resolved directly upon the central axis. Accordingly, therefore, lateral bracing and guides normally necessary to resist undesired torques become unnecessary and resulting frictional stresses upon guide members are completely eliminated. So also, the members or keys which perform the holding action are relieved from all but shearing stress in order to eliminate all possibility of failure and permit association and removal from operative position in complete safety to the operator. In many of the prior constructions with

which I am familiar, various bolts or partly inserted member are employed in such a manner as to resolve the holding stresses laterally with respect to the axis of the drive members, resulting in the application of material forces to limited portions of the holding members. These devices have met with little success in the operation of wells of substantial depth due to the possibility of failure and the resultant hazard to the operator. As the result, the extremely hazardous constructions requiring hooks to be manipulated on the fly have continued in use.

Obviously the invention is not limited to the specific structural arrangement disclosed herein but is capable of other modifications and changes without departing from the spirit and scope of the present invention.

I claim:

1. A safety throw-off device comprising a connecting member, a linearly reciprocable key receiving member adapted to be attached to a source of power for linearly reciprocating said member, a fixed key receiving member, said connecting member being operatively associated with said fixed key receiving member and projecting beyond said fixed member on opposite sides thereof, the portion extending out on one side of said fixed member being operatively associated with said linearly reciprocating member and the portion extending on the other side being adapted to be attached to means for applying actuating force to a pump in a well, said connecting member being reciprocable relative to both said fixed member and said reciprocable key receiving member in a path aligned with the path of movement of said last named member, and means separately operable with respect to either of said key receiving members for selectively preventing said connecting member from shifting relative to said key receiving members in a direction such that the place where said connecting member is adapted to be attached to said means for supplying actuating force is moved away from the key receiving member with respect to which said separately operable means is operated, said separately operable means for preventing shifting including a recess extending transversely of said connecting member, key means receivable in said key receiving members for pivotal movement thereon into and out of said recess, and stop means on each of said key receiving means for limiting the pivotal movement of said key means.

2. A safety throw-off device comprising a connecting member, a linearly reciprocable key receiving member adapted to be attached to a source of power for linearly reciprocating said member, a fixed key receiving member, said connecting member extending through said fixed key receiving member and projecting beyond said fixed member on opposite sides thereof, the portion extending out on one side of said fixed member being telescopically received in said linearly reciprocating member and the portion extending on the other side being adapted to be attached to means for supplying actuating force to a pump in a well, said connecting member being reciprocable relative to both said fixed member and said reciprocable key receiving member in a path aligned with the path of movement of said last named member, and means separately operable with respect to either of said key receiving members for selectively preventing said connecting member from shifting relative to said key receiving members in a direction such that the place where said connecting member is adapted to be

attached to said means for supply actuating force is moved away from the key receiving member with respect to which said separately operable means is operated, said separately operable means for preventing shifting including a recess extending transversely of said connecting member, key means receivable in said key receiving members for pivotal movement thereon into and out of said recess, and stop means on each of said key receiving means for limiting the pivotal movement of said key means.

3. A safety throw-off device comprising a relatively long rod-like connecting member, a linearly reciprocable key receiving member adapted to be attached to a source of power for linearly reciprocating said member, a fixed key receiving member, said connecting member extending through said fixed key receiving member and projecting beyond said fixed member on opposite sides thereof, the portion extending out on one side of said fixed member being telescopically received in said linearly reciprocating member and the portion extending on the other side being adapted to be attached to means for supplying actuating force to a pump in a well, said connecting member being reciprocable longitudinally relative to both said fixed member and said reciprocable key receiving member in a path aligned with the path of movement of said last named member, and means separately operable with respect to either of said key receiving members for selectively preventing said connecting member from shifting relative to said key receiving members in a direction such that the place where said connecting member is adapted to be attached to said means for supplying actuating force is moved away from the key receiving member with respect to which said separately operable means is operated, said separately operable means for preventing shifting including a plurality of spaced recesses extending transversely of said connecting member, key means receivable in said key receiving members for pivotal movement thereon into and out of said recess, and stop means on each of said key receiving means for limiting the pivotal movement of said key means.

4. A safety throw-off device comprising a relatively long rod-like connecting member, a linearly reciprocable key receiving member adapted to be attached to a source of power for linearly reciprocating said member, a fixed key receiving member, said connecting member extending through said fixed key receiving member and projecting beyond said fixed member on opposite sides thereof, the portion extending out on one side of said fixed member being telescopically received in said linearly reciprocating member and the portion extending on the other side being adapted to be attached to means for supplying actuating force to a pump in a well, said connecting member being reciprocable longitudinally relative to both said fixed member and said reciprocable key receiving member in a path aligned with the path of movement of said last named member and the opening in said reciprocable key receiving member in which said connecting member is telescopically received having an enlarged portion providing an annular abutment adapted to be engaged by the underside of an enlarged portion formed on the end of said connecting member extending therein providing an operative connection between said connecting member and said reciprocable key receiving member, and means

separately operable with respect to either of said key receiving members for selectively preventing said connecting member from shifting relative to said key receiving members in a direction such that the place where said connecting member is adapted to be attached to said means for supplying actuating force is moved away from the key receiving member with respect to which said separately operable means is operated, said separately operable means for preventing shifting including a plurality of spaced recesses extending transversely of said connecting member, key means receivable in said key receiving members for pivotal movement thereon into and out of said recess, and stop means on each of said key receiving means for limiting the pivotal movement of said key means.

5. A safety throw-off device comprising a connecting member, a linearly reciprocable key receiving member adapted to be attached to a source of power for linearly reciprocating said member, a fixed key receiving member, said connecting member extending through said fixed key receiving member and projecting beyond said fixed member on opposite sides thereof, the portion extending out on one side of said fixed member being telescopically received in said linearly reciprocating member and the portion extending on the other side being adapted to be attached to means for supplying actuating force to a pump in a well, said connecting member being reciprocable relative to both said fixed member and said reciprocable key receiving member in a path aligned with the path of movement of said last named member, and means separately operable with respect to either of said key receiving members for selectively preventing said connecting member from shifting relative to said key receiving members in a direction such that the place where said connecting member is adapted to be attached to said means for supplying actuating force is moved away from the key receiving member with respect to which said separately operable means is operated, said separately operable means for preventing shifting including a plurality of spaced recesses extending vertically through said connecting member, cooperating vertically extending recesses in each of said key receiving members, key means adapted to be supported on each of said key receiving members for pivotal movement about an axis positioned above and extending transversely of the path of reciprocation of said connecting member, said key means pivoting on said axis in said recess in a key receiving member and into and out of said recess in said connecting member; and said key means having a pair of opposed parallel edges spaced apart in a direction perpendicular to the axis on which said key means pivots, and each of said recesses in said key receiving means being positioned with respect to the associated axis on which said key means pivots so that the end of the said recess remote from the enlarged end of the connecting member is abutted by one of said parallel edges of said key means when the latter extends in said recess in said connecting member with said opposed parallel edges extending vertically, the other of said parallel edges being adapted to be abutted by an end of one of said recesses in the connecting member.

CARL D. WAGNER.

CERTIFICATE OF CORRECTION.

Patent No. 2,336,141.

December 7, 1943.

CARL D. WAGNER.

It is hereby certified that error appears in the printed specification of the above numbered patent requiring correction as follows: Page 2, first column, line 65, for "tubu-" read --tubular--; page 3, second column, line 31, for "applying" read --supplying--; and that the said Letters Patent should be read with this correction therein that the same may conform to the record of the case in the Patent Office.

Signed and sealed this 29th day of February, A. D. 1944.
